(57) **CLAIM**

The ornamental design for a disc player, as shown and described.

DESCRIPTION

FIG. 1 is a perspective view of a disc player showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

Portions of FIGS. 1-6 that are shown as broken lines are for illustrative purpose only and form no part of the claimed design.
